UNITED STATES PATENT OFFICE.

JAMES LOWE PILLING, OF BUCYRUS, OHIO.

AIR-MOTOR.

SPECIFICATION forming part of Letters Patent No. 787,692, dated April 18, 1905.

Application filed September 12, 1903; Serial No. 172,877.

To all whom it may concern:

Be it known that I, JAMES LOWE PILLING, a citizen of the United States, residing at Bucyrus, county of Crawford, State of Ohio, have invented a certain new and useful Improvement in Air-Motors; and I declare the following to be a full, clear, and exact description of the invention, such as will enable others skilled in the art to which it pertains to make and use the same, reference being had to the accompanying drawings, which form a part of this specification.

My invention relates to motors; and it consists in the improvements hereinafter described.

An object of my improvements is to provide an oscillating engine that may be readily and cheaply constructed and which shall be durable and mechanically efficient. I attain this object in the device illustrated in the accompanying drawings, in which—

Figure 1 is a section on the line 1 1 of Fig. 3, a portion of the side plate B being left in full. Fig. 2 is a diagrammatic representation of the ports and inlet-valve, showing the cylinders in their relative position thereto. Fig. 3 is a side elevation with the side plate B removed, looking in the direction of the arrow 2 2 of Fig. 1, one cylinder and a portion 30 of one piston-rod being shown in section. Fig. 4 is a similar view to that of Fig. 3, the side plate B being secured in place, a portion of the plate being broken away to show the passages therein, the cover-plate being removed from the projection B'. Fig. 5 is a section of the projection B' and a portion of the plate B adjacent thereto. This section is taken on the line 5 5 of Fig. 6. Fig. 6 is a section on the line 6 6 of Fig. 5.

The engine herein shown embodying my invention is designed especially as a motor for using compressed air, though steam may be used in it.

A is a hollow casing which may be inclosed by securing the side plate B upon one side thereof. Within the casing A are pivoted two cylinders G and G^a, connected to one crank-pin E upon the crank D upon the main shaft C. The air or working fluid is exhausted from the cylinders into the interior of the

casing A and escapes therefrom through a port A'.

G' G^a are trunnions upon the cylinders G or G^a. One of said trunnions is pivoted in a bearing at the back of the casing A and the other in a bearing in the side plate B.

G⁴ is a pin having a disk G³ at its inner end, which disk is formed into a portion of a sphere at its inner surface and bears against the end of the trunnions G'.

G⁵ is a helical spring surrounding the pin G⁴.

G⁶ is a cap surrounding the pin G⁴ and bearing against the spring G⁵ and engaging by interior screw-threads with screw-threads upon a sleeve or bearing for the trunnions G'.

G⁷ is a set-screw by which the cap G⁶ may be fixed in the position to which it is adjusted.

On the inner surface of the side plate B is secured annular plates P P, the inner surfaces of which are faced off to form bearings 70 for the bearing-surfaces G¹³ upon the cylinders G and G^a, through which surfaces extend the valve-ports G⁹.

The spring G⁵ acts to press the cylinder G toward the plate B and keep the surfaces G¹³ 75 in close contact with the inner surface of the annular plates P. Through the plates P extend ports P', with which register at the proper time the ports G⁹, leading to the cylinders G or G^a.

In the plate B are formed passages B² B³ B⁴ B⁵, Fig. 4. The projection B' from the plate B is formed with a cylindrical bore concentric therewith and with thick walls having longitudinal passages B¹⁴ B¹⁵ B¹⁶ therein. 85 These passages are open at their outer ends at the outer end of the projection B' and are closed by a plate secured upon the outer end of said projection and communicate with the bore of said projection, respectively, by ports H⁵ H⁶ H⁴. The passage B¹⁴ communicates with the passages B³ and B⁵ and the passage B¹⁵ with the passages B² and B⁴.

B²¹ B²¹ B²¹ are diaphragms separating the passages B³ and B⁴ and B² and B⁵. The plates P are secured inside of and contiguous to the diaphragms B²¹ so as to make a tight joint between the edges of said diaphragm and said plates and so as to close the adjacent portions of passages B³ B⁴ and B² and 100 B⁵.

B^5 , which would otherwise be open to the interior of the plate B , so that the cores used in forming the passages may be readily removed. The passage B^{16} communicates directly with the interior of the casing, as indicated most distinctly in Fig. 5.

H^b is a Corliss valve in the bore of the projection B' upon a spindle H , the lower end of which spindle is formed so as to be rectangular in cross-section at the part indicated by H' on the drawings.

The valve H^b is provided with a cavity which fits over the portion H' of the spindle H , so as to be guided thereby. Within the portion H' of the spindle H are formed apertures in which are placed helical springs H^2 , which act against the valve H^b to press the valve-faces H^7 H^8 against the wall of the bore of the projection B' .

B^{19} is the inlet-passage for the actuating fluid, as in this instance compressed air. By turning the spindle H the valve H^b may be turned to a position putting the ports H^6 into communication with the port H^4 , as indicated in Fig. 2, or it may be turned to a similar position, putting the port H^6 in communication with the port H^4 . In the first case the port H^5 is in communication with the actuating fluid and the port H^6 with the exhaust-port H^4 , as indicated in Fig. 2, and in the second case the port H^6 is in communication with such fluid and the port H^5 with the exhaust-port.

B^6 B^9 are ports formed through a plate P adjacent to and upon opposite sides of a diaphragm B^{21} .

B^7 B^8 B^{10} B^{13} B^{11} B^{12} are ports similar to ports B^6 B^9 and similarly located with reference to the other diaphragm B^{21} .

In the position of the valve H^b shown in Fig. 2 the ports B^6 B^7 B^{12} B^{13} are open to the working fluid, and the ports B^8 B^9 B^{10} B^{11} are open to the exhaust-port H^4 .

When a port G^9 of one of the cylinders registers with one of said ports through the plate P , that end of the cylinder receives the working fluid or communicates with the exhaust through said port. The port G^9 at the opposite end of said cylinder is then in communication with the exhaust-port H^4 or with the inlet-passage B^{19} . In one case this is in proper position of the valve H^b to run the motor in one direction. If said valve is turned so as to alter the connection of the ports, as above pointed out, the motor will be in adjustment to run in the opposite direction.

In oscillating engines the cylinders are vibrated about their trunnions by the action of the piston-rod upon the cylinder at that part where said piston-rod passes through the cylinder-head. This action causes the piston-rod to act against the passage through the cylinder-head and enlarges it, causing a leak or injuring the packing in the stuffing-

box. To provide against this, I have provided a piston G^8 of conical or cup-shape form, and the cylinder-head is formed of conical form adapted to extend into the groove of the piston when the piston is at that end of the cylinder, as indicated distinctly in Fig. 3. Thus I am able to obtain a long bearing for the piston-rod in the cylinder-head without extending the cylinder to an objectionable extent in this direction. The cylinder-head at the other end of the cylinder is grooved out in any usual form to receive the nut and projecting part of the piston G^8 , as indicated at G^{10} . The piston-rod F are bored from their inner ends, forming cylindrical cavities F' . At the center of the cylinder-head opposite to that in which is the stuffing-box is secured rigidly a cylindrical rod G^{12} , which extends and fits closely into the cavity F' . This rod serves to strengthen the connection between the piston-rod and cylinder, and it also serves to compress air in the cavity F' and cushion the parts at one end of the piston-stroke, acting as a counterbalance and maintaining the piston-rod parallel, thereby relieving wear on the stuffing-box.

What I claim is—

1. In an oscillating engine, a cylinder having a bearing-surface on one side thereof having the ports therein, a trunnion upon the side of said cylinder opposite to said bearing-surface, a pin bearing at its center and end upon the end of said trunnion, and departing from the surface of the end of said trunnion toward the periphery of its end, and a spring acting to press said pin against said trunnion.

2. In an oscillating engine, a cylinder having a bearing-surface on one side thereof having the ports therein, a trunnion upon the side of said cylinder opposite to said bearing-surface, a pin bearing at its center and end upon the end of said trunnion and departing from the surface of the end of said trunnion toward the periphery of its end, and a spring acting to press said pin against said trunnion, and means for adjusting the tension of said spring.

3. In an oscillating engine, a cylinder having a bearing-surface on one side thereof having ports therein, a trunnion on the other side lying in a cylindrical bearing, a pin having bearing-surfaces on its inner end, a cap over the outer end of said bearing provided with screw-threads engaging with screw-threads connected with said cylinder, a spring bearing against said pin and against said cap and means for securing said cap against accidental movement, for the purpose described.

4. In an oscillating engine, the combination of the pivoted cylinder, a piston therein, a piston-rod extending from said piston through one of the cylinder-heads, said piston-rod being provided with a longitudinal

cavity therein, a rod secured at one end to a cylinder-head and extending inward therefrom and into said cavity, for the purpose described.

5. In an oscillating engine, the combination of the pivoted cylinder, a piston therein, a piston - rod extending from said piston through one of the cylinder-heads, said piston-rod being provided with a longitudinal cavity therein closed at its outer end, a rod secured at one end to a cylinder-head and extending inward therefrom and fitting closely, in said cavity, for the purpose described.

10 6. In an oscillating engine, a casing inclosing the cylinders, a side plate for said casing having passages therein, a projection from

said plate having extensions of said passages therein, an induction-passage for the working fluid leading to the interior of said projection, and a valve mechanism in said projection adapted to adjust the connection of the ports, the passages in said projection opening at the outer end thereof, and a plate adapted to be secured to the outer end of said projection to close said passages. 20 25

In testimony whereof I sign this specification in the presence of two witnesses.

JAMES LOWE PILLING.
